A. KOMP, OF NEW YORK, N. Y.

Letters Patent No. 76,473, dated April 7, 1868.

IMPROVEMENT IN MACHINES FOR ATTACHING SPANGLES TO HOOPS OF SKIRTS.

The Schedule referred to in these Letters Patent and making part of the same.

TO ALL WHOM IT MAY CONCERN:

Be it known that I, A. KOMP, of 184 Fulton street, New York, in the county and State of New York, have invented a new and useful Improvement in Machines for Clasping Hoops to Ladies' Skirts; and I do hereby declare that the following is a full, clear, and exact description thereof, which will enable those skilled in the art to make and use the same, reference being had to the accompanying drawing forming part of this specification, in which drawing—

Figure 1 represents a sectional side elevation of this invention when the hammer is down.

Figure 2 is a similar view of the same when the hammer is up.

Figure 3 is a plan or top view of the spangle-guide.

Similar letters indicate corresponding parts.

This invention relates to certain improvements on that class of machines on which Letters Patent were granted to me, May 7, 1867, and which serve to insert and secure clasps or "spangles" in hoop-skirts, said spangles being used to secure the wires or hoops to the supporting-tapes.

A represents a bed, made of cast iron or any other suitable material. From this bed rises a standard, B, which is cast solid with or otherwise rigidly attached to the same, and which supports the hopper and spout C, through which the spangles pass down to the spangle-guide D, the bottom of said spout being inclined so that the spangles slide down over it by their inherent gravity. While passing down over this inclined surface the majority of the spangles arrange themselves so that their points are turned up and the heads or heaviest parts down, and in this position they slide into the spangle-guide D. This spangle-guide consists of a floor, a, which is inclined both in a longitudinal and in a lateral direction, and which is provided with a rib or flange, b, that is raised above the floor, so as to be able to catch over the heads of the spangles if the same are placed in the proper position. The upper portion of the floor a projects beyond the floor a sufficient distance to admit several spangles, but further down the floor is narrowed, so as to leave room for only one spangle outside the rib. When a spangle slides down over the upper part of the floor, and strikes the rib sideways with one of its points, as shown at 1, in fig. 3, it turns round to the position shown at 2, in said figure, so that its head projects under the rib, and both its points bear against the edge thereof, and in this position the spangle passes safely down through the guide. But if a spangle strikes the rib b in the position shown at 3, fig. 3, it is unable to pass down over the narrow part of the floor a, and it drops off into the trough E.

To effect this purpose, that is to say, to cause all those spangles which are not in the correct position, to drop off into the trough E, the edge of the rib b is curved or scalloped; and furthermore, it is provided with one or more projections, c, the points of which extend clear beyond the edge of the floor a, or nearly so, allowing those spangles to pass which are in the correct position, and therefore retained by their heads catching under the rib, but causing all spangles which are not in the correct position to drop off into the trough. In order to insure this purpose with still greater security, I have also provided the floor a with indentations or small transverse ridges, d, which materially assist in throwing off those spangles that are not in the correct position.

The trough E is secured under the floor a, and its edges project above said floor on both sides, so that the spangles which drop off from the spangle-guide, are caught in the trough, from which they discharge through a suitable aperture into a box, F. This box is secured by a loop and hook to the inner surface of the spangle-guide, and it can be readily taken off for the purpose of returning its contents into the hopper. After leaving the floor a, the spangles enter, one after the other, into the channel e, which forms the lower portion of the spangle-guide, and which turns down in a vertical direction, or nearly so, as clearly shown in figs. 1 and 2. Under the bottom end of this channel is the spangle-carrier, G, which consists of an arm, g, furnished with a spring-jaw, h. The arm g oscillates on a pivot, i, secured in the standard B, motion being imparted to it by a lever or treadle, L, which has its fulcrum on a pivot, j, secured in the standard, and from which extends the hammer H and an arm, k, as clearly shown in figs. 1 and 2. This treadle is subjected to the action of a spring, u, which has a tendency to carry the same back to the position shown in fig. 2. The arm k is provided with a stud, l, which catches into a curved open slot, m, in the end of a rod, n, that is pivoted to the hub of the

spangle-carrier G. From this rod projects a pin, o, which bears on the top edge of a standard, p, that rises from the bed A. By the combined action of the pin o and standard p, the stud l is held in the inner, deepest portion of the slot m, and the motion of the lever L is transmitted to the spangle-carrier; but as soon as the pin o passes beyond the edge of the standard p, the stud l slides in the slot m, and the spangle-carrier remains stationary while the hammer strikes. The spring-jaw h of the spangle-carrier is secured to a slide, q, which moves back and forth in suitable guides attached to the arm g, and which is subjected to the action of a spring, r, having a tendency to force said slide, with its spring-jaw, out to the position which it occupies in fig. 2. In this position said spring-jaw projects beyond the outer end of the arm g, and it strikes the side-pieces of the channel e, so that it opens and receives a spangle in its slot, s, which is just deep enough to admit one spangle. When the rear end of the lever L is raised, the spangle-carrier turns down to the position shown in fig. 1, and as the end of the arm g is withdrawn from the mouth of the channel e, said channel is closed by a spring-gate, M. This gate is secured to a rod, which slides in a suitable bracket attached to an arm, which extends from the standard B, and the spangle-carrier is provided with a lip, t, which bears on the end of said gate and forces the same back, whenever said spangle-carrier arrives in the position shown in fig. 2. As the spangle-carrier moves off from the mouth of the channel e, the spangle received by the spring-jaw h is clamped between said jaw and the end of the arm g, and it is carried down to the anvil, N. This anvil is secured to a standard rising from the bed A, and it serves to support the hoop and the tape, which are to be clasped together by said spangle. The points of the spangle straddle the hoop and penetrate the tape, and as the motion of the lever L progresses, the spring-jaw h is withdrawn, and the hammer H comes down on the spangle-carrier, and clinches the spangle.

The operation of withdrawing the spring-jaw h is effected by a pin, v, which projects from the arm k, and catches in a slot, w, in a rod, x, which connects with the slide q. To this rod is also secured a latch, y, and as the slide q moves back, this latch catches over a pin, z, in the hub of the spangle-carrier, and retains said slide with the spring-jaw h until the spangle-carrier rises again to such a position that the pin z liberates the latch. By these means the spring-jaw is prevented from catching in the tapes of the skirt.

It will be noticed that the spangle-carrier turns down ahead of the hammer, so that the hammer, on coming down, strikes the spangle-carrier, and thereby the spangles are clinched. This purpose is effected by the proportion between the distance of the stud l from the fulcrum of the lever L, and that of the pivot which connects the rod n to the spangle-carrier from the fulcrum of said spangle-carrier.

The hub of the spangle-carrier is provided with two noses, a' b', which act against stops, c' d', projecting from the standard B, one to prevent the spangle-carrier from coming down too close upon the anvil, which would injure the tapes of the skirt, and one to prevent said spangle-carrier from swinging up beyond the desired point, which would be liable to injure the spring-jaw h.

The arm k of the lever L is made in two parts, viz, the main arm k and the secondary part k*, which is connected to the main arm by a pivot, f, and held up to it by a spring, e'. The stud l, which actuates the spangle-carrier, is secured in the part k* of the arm k.

The object of this arrangement is to allow the hammer H to rise a little after the spangle-carrier has come to a stop, said hammer being carried up by its momentum when the machine is operated quick, and by these means the spangle-carrier is permitted to come to a dead stop for a short moment, even if the machine is worked ever so quick, and it is not liable to fly back immediately after it has reached its highest position, thus giving time to the spangles to enter the spring-jaw h.

What I claim as new, and desire to secure by Letters Patent, is—

1. Providing the edge of the rib b of the spangle-guide with one or more projections c, substantially as and for the purpose set forth.
2. The arrangement of indentations or ridges d in the floor a of the spangle-guide, substantially as and for the purpose described.
3. The slotted rod x and pin v, in combination with the slide q, which carries the spring-jaw h of the spangle-carrier, substantially as and for the purpose described.
4. The latch y, in combination with the movable jaw h of the spangle-carrier, substantially as and for the purpose set forth.
5. The curved slot m, stud l, pin o, and standard p, in combination with the arm k, and with the spangle-carrier, substantially as and for the purpose described.
6. The stops c' d', to retain the spangle-carrier at the extreme ends of its stroke, substantially as set forth.
7. The secondary arm k* and spring e', in combination with the main arm k of the lever L, and with the hammer H and spangle-carrier D, substantially as and for the purposes described.

A. KOMP.
